INVENTOR
Thomas E. Murray Jr
BY Paul Blum
his ATTORNEY

UNITED STATES PATENT OFFICE.

THOMAS E. MURRAY, JR., OF BROOKLYN, NEW YORK.

SWITCH.

1,219,134.

Specification of Letters Patent. Patented Mar. 13, 1917.

Application filed June 3, 1916. Serial No. 101,504.

To all whom it may concern:

Be it known that I, THOMAS E. MURRAY, Jr., a citizen of the United States, residing at Brooklyn, in the county of Kings 5 and State of New York, have invented a certain new and useful Improvement in Switches, of which the following is a specification.

The invention relates to switches, and 10 consists in the construction whereby a fuse is carried on the switch lever and the co-operating contacts are simplified.

In the accompanying drawings—

Figure 1 is a plan view of my switch. 15 Figs. 2 and 3 are sections on the line α , α of Fig. 1. Figs. 4 and 5 are sections on the line γ , γ of Fig. 1. In Figs. 2 and 4 the switch is shown open, and in Figs. 3 and 5 the switch is shown closed.

20 Similar numbers of reference indicate like parts.

1 is an inclosing case. 2 indicates, generally, a meter or any other translating device in circuit with the switch. 3 is a base block, preferably of insulating material, on which are contacts 4, 5, respectively connected to the meter leads 6, 7. Also on said block are contacts 8, 9 connected by metal strips 10 to supply leads 11, 12.

30 The switch lever 13 is of insulating material, and is secured at one end to the rocking bar 14. One extremity of bar 14 is pivoted in bracket 15. The other extremity is supported by a rod 16 which extends through a 35 wall of the case 1 and is bent to carry the handle 17 by which the switch is operated. On the upper side of switch lever 13 are two pairs of spring clips 18, 19. On one side of the switch lever 13, Figs. 2 and 3, 40 are two contact plates 22, 23, which are respectively connected to one member of each pair of clips 18, 19. On the other side of

switch lever 13, Figs. 4 and 5, is a contact plate 20, not connected to said clips. The usual metal ring terminals of a fuse 21 of the cartridge type are seated in the pairs of contacts 18, 19.

When the switch lever is closed, Figs. 3 and 5, the lever contact plates 22, 23 co-operate respectively with fixed contacts 4, 8, and the lever contact plate 20 co-operates with fixed contacts 5, 9—thus establishing circuit, which proceeds from supply lead 11, through contacts 8, 22, to fuse 21, through said fuse to contacts 23, 4, to translating device 2, and thence to contact 5, contact plate 20, contact 9, and supply lead 12.

I claim:

1. A switch, comprising two pairs of fixed contacts, a pivoted switch lever, contacts on said lever respectively co-operating with one member of each of said pairs of fixed contacts, a fuse on said lever having its terminals connected to said lever contacts, and a contact on said lever co-operating with both remaining members of said pairs of fixed contacts.

2. A switch, comprising two pairs of fixed contacts, a pivoted switch lever, two spring clips on the outer face of said lever, contacts on said lever respectively connected to one member of each clip and respectively co-operating with one member of each of said pairs of fixed contacts, a fuse removably seated in said clips, and a contact on said lever co-operating with both remaining members of said pairs of fixed contacts.

In testimony whereof I have affixed my signature in presence of two witnesses.

THOMAS E. MURRAY, JR.

Witnesses:

GERTRUDE T. PORTER,
MAY T. McGARRY.
